PRESSURE SELECTOR FOR WRINGERS

Edwin E. Foster, Austin, Tex.

Application October 8, 1945, Serial No. 620,885

10 Claims. (Cl. 68—262)

1

This invention relates to pressure selectors for wringers and the like in which the usual pressure adjustment device of a wringer is replaced by an improved adjustor in the form of a pressure selector for adjusting the force of the spring of the wringer.

An object of this invention is to provide the pressure leaf spring for the rolls with a variable fulcrum device to impart the effect of varying the effective leverage of the leaf spring which is operative between the stationary top of the wringer and the movable upper roll. In other words, the invention aims to provide a system for adjusting the wringer pressure of a leaf spring type wringer such as shown for example in Patent No. 2,312,762, March 2, 1943, by means to utilize the center of the spring for low pressure and by using two points about half way between the center and the ends of the spring for medium pressure, and by shifting the fulcrum still further towards the ends of the leaf spring for high pressure. In the known types of wringers, the adjusting of the pressure is accomplished by a screw member which tightens down further to load the spring for the higher pressures and this preloading of the spring renders it hard to operate the toggle to reset the latter on high and medium pressures. A further object of the invention therefore resides in providing a pressure selector which can be easily moved when the toggle is released and the toggle can be reset much easier. A still further object of the invention resides in providing a device which will impart to the leaf spring different forces, thereby imparting the effect of having three different springs, each of different strength, which is due to the use of a different leverage for each pressure position.

The important feature of the invention therefore resides in the provision of an adjustable fulcrum or different fulcrum positions on the leaf spring to obtain different effective pressures on the wringer rolls.

Further objects will be apparent from the following description when considered in connection with the accompanying drawings in which:

Figure 1 is a side view partly in section of the top portion of the wringer showing one form of pressure selector.

Fig. 2 is an end view partly in section of the top portion of the wringer.

Fig. 3 is a plan view partly in section of the pressure selector.

Fig. 4 is a side view partly in section of the top portion of the wringer showing a second form of pressure selector.

2

Fig. 5 is an end view partly in section of the wringer of Fig. 4.

Fig. 6 is a plan view partly in section of the pressure selector of Figs. 4 and 5, and

5 Fig. 7 is an exploded perspective view of a detail.

A U-shaped cam member 1 is suitably secured, for instance by welding, to the top member 2 of the wringer, and this cam member is 10 provided with surfaces 16, 17 and 18 at the left end, Fig. 1, and surfaces 19, 20, 21 and 22 at the right end.

A shiftable or adjustable lever or member comprises a pair of shifting links 3 and auxiliary shifting links 4 interconnected by fulcrum pins 5, 6 and 7 of which pin 5 at the left end, Fig. 8, interconnects links 3, pin 6 interconnects links 3 and 4, and pin 7 interconnects links 4. The shifting links 3 converge at 23 to form a projecting arm 24 terminating in a control knob 8. The arm 24 extends through a slot 9 in the top member 2.

A fourth pivot pin 10 is clamped to the center of the leaf spring 25 by means of a spring clip 11. A round headed rivet 12, Fig. 7, is bradded to the pin 10 and fits into a depression 26 in the top of the leaf spring. The pin 10 can move downward, Fig. 1, in a pair of slots 13 in the top member 1 and this pin 10 can move downward 20 in the slots 13 as thicker material is introduced between the rolls of the wringer and the ends of the leaf spring move upward about the fulcrum points 5 and 7 in the high pressure position.

The spring 25 may be set to impart any number 35 of pressures or forces on the wringer rolls dependent upon the number of cam surfaces which are provided in the U-shaped member 1 but for the usual type of wringer for domestic and commercial use three different pressure positions are sufficient as indicated in Fig. 3 by the terms "High," "Medium" and "Low," and of which the positions for the actuating or setting knob 8 are indicated in Fig. 1 by H, M and L, which correspond to the first-mentioned positions for Fig. 3. Fig. 1 also shows the usual pressure release bar 14 and the toggle member 15.

The device operates as follows:

Fig. 1 shows the pressure selector in its high pressure position in which the spring 25 has its fulcrum points at the full line pin positions 5 and 7, the latter bearing against the surfaces 16 and 22 respectively of the cam member 1. In this position pin 6 is not in contact with the cam member 1. To change to medium pressure, the pressure release bar 14 is touched lightly to open the toggle member 15 to remove the pressure of

the spring 25, and with the pressure thus removed the knob 8 is shifted to the right, Fig. 1, from the H to the M position. The toggle member 15 is then closed and a medium pressure will be set up between the rolls due to the shifting of the fulcrum points on the spring 25. In the M position the fulcrum pins have been shifted by the levers 3 and 4 from the full line positions to the dotted line positions 5', 6' and 7' in which new fulcrums 5' and 6' are in contact with the cam surfaces 17 and 20 respectively, the pin 7 at dotted line position 7' being ineffective as it does not react against the member 1. The new fulcrum points 5' and 6' being nearer the center of the leaf spring 25, the latter will impart a smaller or reduced pressure relative to the high pressure position. If it is desired to reduce the pressure still further or to its minimum amount, the knob 8 will be shifted farther to the right, Fig. 1, to the position L, and in this position the pins 5, 6 and 7 have shifted to the positions 5'', 6'' and 7'' in which all three pins are ineffective relative to member 1. Therefore in the L position the spring 25 will flex about the center fulcrum 10. The fulcrum 10 was of course ineffective in the M and H positions.

It will be apparent that any number of further intermediate positions are possible by providing suitable cam surfaces on the member 1, and the positions may be located at other places than those shown.

In a preferred construction of the pressure selector, the member for shifting the fulcrum points on the spring may be pivotally mounted instead of slidably secured in the top of the wringer. Figs. 4 to 6 illustrate a preferred pivoted fulcrum shifter applied to the top member 2 and a standard leaf spring 25.

In the top member 2 a slot 26 is provided at the toggle end thereof. Extending through this slot is a selector finger 27 integral with a selector lever or member 28 which is easily moved to the different pressure positions when the toggle member, not shown, is released. This selector finger 27 is in such a position that it can be easily operated with the thumb or forefinger of the same hand that is holding the toggle member just prior to setting the toggle. In Fig. 6 the selector finger 27 is in the full line position 43, which is on medium pressure. In this position bosses or fulcrum points or pins 29 and 30 connected to the member 28 are directly over the leaf spring 25 and act as the double fulcrum for the leaf spring to pivot about as bearing blocks 31 and 32 move upward as the clothes force the upper roll 10 upward. The center pivot 33 of the leaf spring moves downward in a slot 34 in a bracket 35 which is spot welded to a cam member or bracket 36. This double bracket 36 is part of a stamping which is also provided with depressed portions 37 and 38 against which the pressure of the fulcrums will be applied, as will be described. During this operation the pivot pin 33 is held firmly anchored to the center of the spring 25 by means of a U-shaped stamped member 39 which extends completely underneath the leaf spring and is provided with an interlocking washer 40 on top of the leaf spring. This washer 40 is provided with an indentation which fits into the indentation in the center of the leaf spring. The pin 33 fits through holes in the ends of the U-shaped member 39 and locks the washer 40 and the U-shaped member 39 to the center of the leaf spring. The washer 40 is provided with notches on the forward and back edges into which the upright por-

tions of the U-shaped member 39 fits, to prevent the member 39 from moving sideways. When the selector finger 27 is moved to the dotted line position 44 coinciding with an indicator mark 5 "High," Fig. 6, a second set of bosses or fulcrum points or pins 41 and 42 will be directly over the center of the leaf spring 25 and are nearer the ends of the leaf spring. Therefore, any upward movement of the roll 10 will be opposed by a stiffer spring on account of the smaller leverage. During the time that the leaf spring 25 is pivoting about the two fulcrums 41 and 42, the center pivot pin 33 will move downward in the slot 34 of the bracket 35. The portions of the spring directly under the bosses 29 and 30 will, of course, move away from the bosses 29 and 30. Therefore, the fact that they are still partly over the spring in the "High" position will not affect the spring. When the selector finger 27 is moved to the dotted line position 45, marked "Low," all of the bosses 29, 30, 41 and 42 will be off of the spring 25 so that any upward movement of the upper roll will cause the spring 25 to flex about the center fulcrum 33, which will press against the upper edge 25 of the slot 34 in the bracket 35. This center fulcrum 33 will, of course, give the effect of a soft spring, which is more suitable for woolen clothes which should not be subjected to extreme pressures.

30 A relatively weak guide spring 46 is clamped to the member 36 by means of a screw 47 to keep the leaf spring 25 from moving clockwise about the point 33 during the time the toggle member is open and the selector 27 is being shifted. Without this guide spring 46 the leaf spring 25 would have a tendency to move up into the path of the bosses 42 and 30 and interfere with the moving of the selector member 43. The selector member 43 is pivoted to the top member 1 by means of a shoulder screw 48. The bosses 29, 30, 41 and 42 are riveted or otherwise permanently fastened to the selector member 28.

As shown in Fig. 6, the lever 28 is substantially S-shaped so that in the "Low" position all the projecting points will be out of contact with the spring and in the other two positions one of the two points 29 and 30 or 41 and 42 will be in contact with the spring 25. It is obvious that in the "High" position it is immaterial if points 30 and 29 contact the spring since the leverage is effective from the points 41 and 42. It is also obvious that additional projecting pins such as 29, 30, 41 and 42 may be provided depending upon the number of adjustments which may be desired. It would also be obvious to have a series of closely spaced projecting pins or points so that almost any degree of force may be placed on the rollers within the limits of the effective effort of the 60 spring.

It is obvious that further modifications are possible within the scope of the appended claims.

I claim as my invention:

1. In a spring pressed roller type wringer having a top member, a pressure selector having a member secured to the under surface of the top member and provided with projecting members, and an adjustable member having a plurality of fulcrum points thereon to contact the spring for intermediate and high pressures on the rollers of the wringer and movable to a low pressure position, said fulcrum points cooperating with said projecting members when the fulcrum points are moved to vary the effective leverage of the spring 75 for said intermediate and high pressures and

being out of pressure contact with the spring in the low pressure position.

2. In a spring pressed roller type wringer having a leaf spring with pressure reaction at the center for low pressure, a pressure selector comprising an adjustable member having a plurality of fulcrum points secured thereto adapted to bear against the spring for intermediate and high pressures, said member being shiftable to adjust one or the other of the fulcrum points in contact with the spring spaced from the center to vary the effective leverage of the spring for said intermediate and high pressures.

3. In combination with a wringer having a leaf spring pivoted intermediate its ends to impart a pressure on the rolls of the wringer, a pressure selector shiftably mounted in the wringer and cooperating with the spring to shorten the effective leverage of the spring for higher pressures than that pressure imparted by the spring from its intermediate effective point.

4. A pressure selector for the leaf spring of a roller type wringer comprising a cam member secured above the spring, and means having a plurality of fulcrum points to contact the spring at points between the center and each end of the spring, said means being shiftable between the cam member and the spring to adjust a respective fulcrum point relative to the cam member to vary the effective leverage of the spring and thereby the force of the spring.

5. A pressure selector according to claim 4, in which the means are shiftable longitudinally relative to the length of the spring.

6. A pressure selector according to claim 4, in which the means are slidably mounted to slide relative to the spring.

7. A pressure selector for the leaf spring of a roller type wringer comprising a member having a pair of projecting portions and provided above the spring, a lever in engagement with said projecting portions and having a plurality of depending members secured adjacent each end thereof, and means for pivotally mounting the lever at a point coinciding with the center point of leverage of the spring, said lever being rotatably adjustable to move the depending members in contact

with the spring to change the effective leverage of the spring from the center point to an intermediate point.

8. A pressure selector for the leaf spring of a roller type wringer comprising a member having a pair of projecting portions and provided above the spring, a lever in engagement with said projecting portions and having a substantial S-shape and a plurality of depending pins secured adjacent to each end thereof, and means for pivotally mounting the lever at a point coinciding with the center point of leverage of the spring, said lever being rotatably adjustable to move the depending pins in contact with the spring to change the effective leverage of the spring from the center point to an intermediate point.

9. A pressure selector according to claim 8, in a wringer having a casing with a slot in which the lever is provided with a portion at one end which projects through said slot in said casing to permit adjustment of the lever and depending pins.

10. A pressure selector for the spring of a roller type wringer in which the spring has a center fulcrum point comprising a shiftably mounted member having a plurality of fulcrum points to contact the spring at points intermediate the center and the ends of the spring for intermediate and high pressures on the rollers of the wringer, said fulcrum points varying the effective leverage of the spring for said intermediate and high pressures, and means for shifting said member and fulcrum points relative to said spring.
